[57] CLAIM

The ornamental design for a convertible doll, as shown and described.

DESCRIPTION

FIG. 1 is a front-view of a convertible doll showing our new design;

FIG. 2 is a right side-view of FIG. 1, the left side is a mirror image thereto;

FIG. 3 is a rear-view of FIG. 1;

FIG. 4 is a front-view of the convertible doll shown in an inverted position with the skirt of the dress pulled down over the head of the doll shown in FIG. 1;

FIG. 5 is a right side-view of FIG. 4, the left side is a mirror image thereto;

FIG. 6 is a rear-view of FIG. 4;

FIG. 7 is a rear-view of FIG. 4 with the bonnet shown in an alternate position over the face shown in FIG. 4;

FIG. 8 is a right side-view of FIG. 7, the left side-view is a mirror image thereto; and,

FIG. 9 is a rear-view of FIG. 7.
